United States Patent Office

Des. 179,334
Patented Nov. 27, 1956

179,334

FIRE POT

Milo E. Webster, Rochester, N. Y., assignor to Otto
Bernz Co., Rochester, N. Y., a corporation

Application February 27, 1956, Serial No. 40,366

Term of patent 14 years

(Cl. D81—10)

Fig. 1 is a side perspective view of a fire pot showing my new design, the side opposite thereto being the same except for the on-and-off control appearing at the right.

Fig. 2 is an elevational view as seen from the left of Fig. 1.

I claim:

The ornamental design for a fire pot, as shown and described.
